UNITED STATES PATENT OFFICE.

JOHN WALKER, JR., OF PHILADELPHIA, PENNSYLVANIA, ASSIGNOR TO WALKER MFG. CO., INCORPORATED, OF PHILADELPHIA, PENNSYLVANIA, A CORPORATION OF PENNSYLVANIA.

HEDDLE-FRAME.

1,129,767.

Specification of Letters Patent. Patented Feb. 23, 1915.

Application filed July 23, 1914. Serial No. 852,689.

To all whom it may concern:

Be it known that I, JOHN WALKER, Jr., a citizen of the United States, residing in Philadelphia, Pennsylvania, have invented 5 certain Improvements in Heddle-Frames, of which the following is a specification.

One object of my invention is to produce a durable and inexpensive heddle frame for looms in which the heddles may be freely 10 moved, in order that the weaver can easily get hold of the portions of the warp threads back of the heddle frame or when for any other reason it is desired to move the heddles or change their position in the frame. 15 Another object of the invention is to so construct the device that the means which permit the movement of the heddles shall not interfere with the necessary free movement of the heddle frames during their 20 alternate rising and falling movement under operating conditions.

A still further object of the invention is to prevent one heddle frame from injuring another during the operation in the loom. 25 These objects and other advantageous ends I attain as hereinafter set forth reference being had to the accompanying drawing in which,

Figure 1 is an elevation of a heddle frame 30 showing my invention as applied thereto; Fig. 2 is an enlarged elevation, partly in section, further illustrating my invention; Fig. 3 is an inverted plan of the parts shown in Fig. 2; the heddle bar being omitted for 35 clearness; and Fig. 4 is a section on the line *a—a*, Fig. 2.

Referring to the above drawings;—the frame consists of two parallel beams 1 and 2 preferably made of wood and secured together at their ends by two metallic tie members 3 and 4 each having holes at their upper and lower portions through which the ends of two parallel heddle supporting bars 5 and 6 extend. These bars in the present instance 45 have holes at their outer ends for the reception of spring wire clamps 7 designed to prevent their longitudinal movement.

As a means for supporting the heddle bars 5 and 6 at points within the frame I provide 50 a number of similar devices shown in detail in Figs. 2, 3 and 4, and for their reception the frame beam 1 is recessed at 8 to receive a flat metal strip 9 which has its outer face flush with the inner edge 10 of the said beam. 55 Slidably mounted on the outer flat surface

of the strip 9 is a flat sliding metal plate 11 slotted at 12 and 13 and having riveted or otherwise secured to it a depending hook 15 placed at a point between said slots. This hook has an opening 16 shaped to receive the 60 heddle supporting bar 5 (Figs. 2 and 4). The slidable plate 11 is movably attached to the strip 9 by screws 17 and 18 which respectively pass through the slots 12 and 13 and enter holes in said strip. The parts are so 65 arranged and proportioned that when the hook 15 is in its normal position, the screws will be substantially in the middle of the slots 12 and 13, as shown in full lines in Figs. 2 and 3, and the friction between the 70 slidable plate 11 and the strip 9 may be regulated by tightening or loosening these screws.

The heddles may be of any suitable construction and are suspended between the supporting bars 5 and 6 in the usual manner 75 so that they may be moved longitudinally thereon.

When in use, those heddles which are adjacent the hooks 15 of the several supporting devices may be conveniently separated by 80 the weaver, since it is merely necessary to push them along the supporting rods 5 and 6 until their pressure against said hooks is sufficient to move the latter and thereby form an opening through which the weaver may 85 insert his hand to repair or tie any ends of warp which have broken during the weaving operation. In Fig. 2 the hook 15 is shown in two positions of which the normal or central is shown in full lines while the broken 90 lines illustrate said hook in a position into which it may be moved.

It will be noted (Fig. 3) that by having the contacting faces of the slidable plate 11 and the metallic strip 9 flat the hook 15 cannot 95 rock or otherwise move beyond the planes of the side surfaces of the frame beams 1 and 2. This is a very important and valuable feature of my invention, since heddle frames often have to be placed very 100 close together and if a portion of one frame should extend into the path of an adjacent frame (as frequently occurs with heddle frames heretofore in use) it would obviously cause injury thereto. With my invention the 105 hooks are so supported that they cannot extend into each other's path of movement.

Another feature of my invention resides in the fact that its construction is such that it cannot collect and become clogged by 110

"fly" fibers which are present during weaving, for it will be observed that the strip 9 is set flush within the recess of the beam 1 so that any fly fibers settling thereon are either brushed off by the movement of the 5 slidable plate 11 or can be easily removed. As before stated, different degrees of friction may be caused between the strip 9 and slidable plate 11 by means of the screws 17 10 and 18 and in some cases the friction may be made so intense that a number of the heddles may be bunched between the upper and lower hooks; thereby crowding or bunching the warp to produce rib weaves.

15 In the drawings I have shown a frame having four heddle bar-supporting devices, two at the top and two at the bottom, but it will be understood that any number may be employed without departing from my 20 invention.

25 While I have described one of the supporting devices as secured to the bar 1, it will be understood that in securing it to the beam 2, the latter is recessed to receive its strip in the same manner as indicated at 8 in connection with the beam 1, Fig. 2.

I claim:—

30 1. The combination in heddle mechanism of a frame; a heddle-supporting bar; a plate having a hook for holding said bar; and means for holding said plate in slidable engagement with said frame, the same being adjustable to vary the friction between the plate and frame.

35 2. The combination in heddle mechanism of a frame having a flat portion; a heddle-supporting bar; a flat plate slidable on said flat portion of the frame and having a hook extending therefrom for holding said bar; and means for holding said plate in sliding 40 engagement with said flat portion.

45 3. The combination in a heddle frame having a heddle supporting bar of a slidable plate having slots therein; means extending through the slots for movably connecting the plate to the frame; and a hook on said plate placed to hold said heddle supporting bar.

50 4. The combination in a heddle frame of a member having a recess; a flat strip fitting said recess; a slidable plate having a flat surface for engagement with said strip; a heddle supporting bar; a hook on said

plate for holding the bar; and means for limiting the movement of said plate and 55 for securing it to the recessed member.

5. The combination in a heddle frame of a member having a recess; a flat strip fitting said recess; a slotted slidable plate having a flat surface for engagement with 60 said strip; a heddle supporting bar; a hook on said slotted slidable plate for holding the bar; with means extending through said slots and strip for securing the plate and strip to said recessed member and for limiting the amount of movement of said slidable plate.

6. The combination in a heddle frame of a beam having a recess; a flat plate fitting said recess; a slotted plate having a flat surface 70 slidably engaging said strip; screws extending through the slots in said plate and into said beam; a heddle supporting bar; and a hook rigidly secured to said slidable plate for holding said bar. 75

7. The combination in a heddle frame of a beam having a recess; a flat plate fitting said recess; a slotted plate having a flat surface slidably engaging with said strip; screws extending through the slots in the 80 plate and into said beam; a heddle supporting bar; and a hook for holding said bar rigidly secured to said slidable plate and having a flat surface in contact with a flat surface on the slidable plate. 85

8. The combination, in a heddle frame having a heddle supporting bar, of a plate slidably mounted on the frame and having a hook for holding said bar; and adjustable means passing through the plate for varying the friction between it and the frame. 90

9. The combination in a heddle frame of a member having a recess; a flat strip fitting said recess; a plate having a flat surface slidably engaging said strip; a heddle 95 supporting bar; a hook on said plate for holding the bar; and means for varying the friction between the flat strip and the slidable plate.

In testimony whereof, I have signed my 100 name to this specification, in the presence of two subscribing witnesses.

JOHN WALKER, Jr.
